[57] **ABSTRACT**

The improved device consists of an elastic fastening made of spring steel rod. The rod is bent to form a loop portion which rides over and sits on the bottom flange of the rail. The two ends of the loop are bent downwardly thus providing humps. Then the ends of the same rod after bending downwardly are shaped each into a coil. The ends of the coil then project towards the loop and lie within the loop. These projections form legs. This elastic fastening is secured to the sleeper by a securing device such that the loop rides and sits on the bottom flange of the rail. The legs are forced down by the securing device such that the ends of the legs bear against the edge of the foot, i.e. the bottom flange of the rail. The loop thus holds down or presses the rail while the legs bearing against the foot of the rail help to maintain the gauge of the rail.

DEVICE FOR HOLDING DOWN THE RAIL TO THE SLEEPER IN A RAILWAY TRACK

The device has for its object to press the rail and at the same time to maintain the gauge of the two rails in the track. The device will absorb vibrations caused in the rail when the train passes over the rail track.

PRIOR ART

In order to absorb the vibrations in the rail track it is known to use a sole pad of rubber or similar material placed between the rail and the sleeper which pad provides an elastic vibration absorbant seating.

It has also been proposed to use elastic fastenings of different types. In one form this comprises a plate forming an upper leg, which is then bent to form a lower leg, the upper leg being adapted to hold down the foot of the rail, the lower leg providing an elastic sideways check on the rail, both the said legs being secured to the sleeper through a bolt.

Another type of elastic fastening comprises a clamp of resilient material which consists of three portions of which one portion exerts a bearing pressure on the upper surface of the bottom flange on one side of the rail, while another portion exerts a bearing pressure on the upper surface of the bottom flange on the opposite side of the rail. Then there is a third portion which with the fastener under the state of stress is adapted to be engaged by a pin inserted in a hole in the sleeper.

Another known type of such fastening is a British type called "PANDROL" (Trademark) which comprises a single looped bar forming two legs and a loop, substantially like the formation of the letter C with its ends extended. The curved portion is seated on the foot of the rail to hold down the rail, one leg thereof engaging a bore in a lug or protrusion formed with the sleeper, the second leg being free and kept on the sleeper.

Another known type comprises a clamp having a curved member with its free ends bent to embrace or grip the foot of the rail, said curved member being secured to the sleeper by passing the same round a peg fitted on the side of the sleeper.

According to this invention the device for holding down the rail to the sleeper in a railway track comprises an elastic fastening formed from a spring steel rod bent to form a main loop to function as a pressing member when mounted on the upper surface of the bottom flange on one side of the rail, the ends of the rod beyond the said main loop being then bent downwardly of the plane of the main loop and further bent upwardly to form vertically disposed complete coils, the extensions of the said coils being then bent down to form legs to bear directly against the edge of the foot of the rail, whereby the lateral forces are elastically transmitted from the rail through the legs to the sleeper via the coils and means for securing the elastic fastening to the rail sleeper comprise a body having sloping surfaces over which the legs of the elastic fastening are constrained to slide over to engage recesses formed in the said body, the recesses being in a plane that when occupied by the legs, the said legs are depressed and bear against the edge of the rail flange in which state the main loop exerts downward pressure on the foot of the rail to hold the said rail firmly against the sleeper and the legs butt or bear against the foot of the rail to maintain the gauge of the track and to absorb the lateral forces.

The invention will now be more fully described with reference to the accompanying drawings which illustrate one preferred embodiment of carrying out the invention:

5 FIG. 1 shows in perspective the elastic fastening without securing device;

FIG. 2 shows end view of the device of FIG. 1 fitted on a rail laid on a sleeper;

10 FIG. 3 shows in perspective the elastic fastening device with the securing device as fitted on a rail;

FIG. 4 shows end view of an alternative form of securing device and also shows the legs of the fastening device being forced in position of use.

15 Referring to the drawings, the elastic fastening is made of spring steel rod of round section bent to form a main loop C in the shape of a horse shoe which will sit over the foot or bottom flange on one side of the rail R and function as a pressing member. When in use, the said main loop C rides over the bottom flange and is in a plane which forms an acute angle with the foot of the rail.

20 The ends of the said main loop are then bent downwardly to form humps H and then coiled as indicated by D and E. These coils may extend above the plane of the main loop, being in a substantially vertical plane as shown. The ends of the coils are then turned towards the main loop to lie within the region of the main loop. These are in the form of legs marked F and G. In the stressed condition these legs are disposed below the plane of the main loop C, as shown in FIG. 2 so that the ends of the said legs F and G can bear against the edge of the foot of the rail R and maintain the gauge of the track. The legs F and G lie within the 30 region of the main loop and are spaced from each other and are secured to the rail by a device shown in one of the FIGS. 3 and 4.

25 The securing device used in combination with the fastening device comprises a body T having a jaw with two downwardly sloping surfaces U leading to a narrow mouth and beyond the said mouth are formed recesses V. The legs F and G are forced down the sloping surfaces by any convenient form of tool. The legs are constrained to slip down through the narrow mouth and then push out in which process the said legs engage recesses V.

30 In the securing device shown in FIG. 4, the device comprises a body Z with mushroom head shaped section having outwardly sloping surfaces W approaching recesses V in which the legs F and G finally rest.

35 When the legs occupy the recesses in the body T or Z, the said legs are in a plane that they bear against the edge of the foot of the rail. In this position, the legs are depressed and the main loop exerts downward pressure on the foot of the rail to hold the said rail firmly against the sleeper.

40 In both the cases, FIGS. 3 and 4, the legs slide over the sloping surfaces and whereas in the device of FIG. 3, the legs F and G are forced together, in the case of FIG. 4, the legs are forced apart before getting seated finally in the recesses V.

45 The main loop C will exert a toe load on the rail of about 800 to 1,000 k.g. and even with the action of the rail vibrations, the toe load of the loop C on the rail is maintained fairly constant as the vibrational amplitudes are comparatively of a small magnitude with reference to its own toe load deflection.

The provision of the loops D and E enables a greater deflection for the same toe load which is beneficial both from the point of view of wider tolerances in manufacture as well as from the point of view of minimizing the vertical stresses which essentially provides for longer fatigue life.

In the stressed condition, the forward ends of the legs F and G take care of the occasional lateral forces developed in the rail by the passage of the train. These lateral forces are elastically transmitted through the loops on to the prepared surface P of the sleeper S housing the heel N.

In track circuited sections requiring insulating liners between the device and the rail, the main loop will ride over the liner placed on the foot of the rail while the legs will butt against the edge of the rail through the said liner.

What is claimed is:

1. A device for holding down the rail to the sleeper in a railway track comprising an elastic fastening formed from a spring steel rod bent to form a main loop to function as a pressing member when mounted on the upper surface of the bottom flange on one side of the rail, the ends of the rod beyond the said main loop being then bent downwardly of the plane of the main loop and further bent upwardly to form vertically disposed complete coils, the extensions of the said coils being then bent down to form legs to bear directly against the edge of the foot of the rail, whereby the lateral forces are elastically transmitted from the rail through the legs to the sleeper via the coils, and means

for securing the elastic fastening to the rail sleeper comprise a body having sloping surfaces over which the legs of the elastic fastening are constrained to slide over to engage recesses formed in the said body, the recesses

5 being in a plane that when occupied by the legs, the said legs are depressed and bear against the edge of the rail flange, in which state the main loop exerts downward pressure on the foot of the rail to hold the said rail firmly against the sleeper and the legs butt or bear against the foot of the rail to maintain the gauge of the track and to absorb the lateral forces.

10 2. A device of claim 1 in which the securing device used in combination with the fastening device comprises a body having a jaw with two downwardly sloping surfaces leading into a narrow mouth and beyond the said mouth are formed recesses and wherein when the legs are forced down the sloping surfaces, the said legs are constrained to slip down through the narrow mouth and then push out in which process the said legs engage the recesses, and when the legs occupy the recesses in the body, the said legs are in a plane that they bear against the edge of the foot of the rail.

15 25 3. A device of claim 1 in which the securing device comprises a body having a head with two oppositely disposed outwardly sloping surfaces approaching recesses in which the legs of the elastic fastener finally rest, and when the legs occupy the recesses in the body, the legs are in a plane that they bear against the edge of the foot of the rail.
